ATTACHMENT PLUG

John P. Ogle, Glendale, Calif., assignor to Josephine K. Kafoury, doing business as Cord-Away Mfg. Co., Los Angeles, Calif.

Application August 23, 1937, Serial No. 166,467

2 Claims. (Cl. 173—332)

The principal object of my invention is the provision of an attachment plug of the post insertion type and of universal adaptation and application to the various electric devices and appliances the market affords.

An important object is the provision of a plug of said characteristics obviating all necessity for separate plugs for the different devices and appliances, and by the same analogy standardizing such plugs, it being common knowledge that many are equipped for attachment to plugs embracing a pair of round posts $\frac{1}{8}$ inch in diameter set at $\frac{1}{2}$ inch centers, others of like size but set at various centers such as $\frac{1}{8}$ th inch, $\frac{5}{8}$ th inch and $\frac{11}{16}$ th inch, while still other embrace similar posts in size as high as $\frac{7}{16}$ th inch and having identical varying center spacing. Additionally, we find the flat type post of the commonly styled "duck-bill" variety, some positioned on a horizontal plane, others on a vertical plane, in either case, of varying widths and center spacing. Some devices require the so called standard plug, others the "pony" plug, while others embrace varying sizes and styles differing from the foregoing.

Thus, it is an important object of the herein invention to provide an attachment plug embracing structural characteristics enabling the same to readily serve as a connecting medium to or from the source of electrical energy for the interconnecting of a multiplicity of different devices and appliances such as are usually found in the average home, office or business, electric toasters, lamps, irons, washing machines, fans, solder pots, etc., for example, and this, regardless of the design and shape of the connecting medium thereunto embraced.

A further important object is the provision of an attachment plug servicing the various styles of commercial convenient outlets, a great number of which for varying purposes, radio connections, for example, are being installed daily in the homes, offices and business places, etc., and is interchangeable therewith.

A still further purpose of the present invention is to provide an attachment plug possessing a greater contact area superimposed under tension, and whereby a more efficient operating functioning of the connected device or appliance, as the case may be, results.

A further object of the invention is the provision of an attachment plug possessing increased load carrying properties coupled with a marked decrease in heat retention powers, in comparison with attachment plugs for like purposes in com-

mon use, and whereby the efficiency of the plug is materially increased.

And a further highly important object is the provision of an attachment plug affording a greater measure of safety and accident prevention through the practical elimination of both fire and accident hazards so common with the average attachment plug for like purposes in use.

Other objects and advantages of the invention will more fully appear as this specification proceeds and as is set forth in the appended claims.

I attain these objects by the device disclosed in the accompanying drawing, in which:

Figure 1 is a plan view of my invention. It is shown detachably connectable by way of example, 15 to a conventional hot plate.

Figures 2 to 7 inclusive are sectional views respectively in numerical sequence, to-wit:

Figure 2 on line 2—2 of Fig. 1;

Figure 3 on line 3—3 of Fig. 2;

20

Figure 4 on line 4—4 of Fig. 3;

Figure 5 on line 5—5 of Fig. 3;

Figure 6 on line 6—6 of Fig. 3;

Figure 7 on line 7—7 of Fig. 3;

Figure 8 is a broken-away elevation of another 25 form of my invention, and

Figure 9 is a sectional view on line 9—9 of Fig. 8.

Similar numerals of reference indicate like parts thruout the several views, the invention thus comprising a sectional body of cooperating halves A and B respectively and fulcrumed at 10. In process of manufacture, each of said halves are formed of separate portions, the half A by the portions 11 and 12 which are held in secured relation to one another by means of a bolt 13 and a dowel pin 14, the half B comprising portions 15 and 16 joined together by a bolt 17 and a dowel pin 18. The former are shaped adjacent their meeting edges to provide a longitudinal cavity 19 having a contact clip 20 interposed in its forward end. The latter is arranged to provide a cavity 21 in which is interposed a contact clip 22.

The rear ends of said cavities 19 and 21 provide 25 respective passages for the entrance of wires 23 and 24 which are connected to the contact clips 20 and 22 by suitable means as by bolts 25 and 26 respectively.

It will be noted that the contact clips are 30 variable in shape so as to accommodate the entrance of appliance contact posts or prongs of various shape and spacing, as are indicated at 20' and 22' for example, the cavities 19 and 21 providing ample clearance to permit the spreading 35

of said clips as required in self-adjustable engagement with said prongs in the process of entering the same, the cooperating influence of said variable designed cavities (Fig. 6) and said self-adjustable spreading means inherent in said clips providing a basically designed attachment plug for universal adaptation to electric appliances and devices of the post or prong insertion type.

Being fulcrumed at 10, the respective halves A and B when interconnected, are readily adaptable to be spread apart at either end. In as much, however, that they are normally urged together at their forward end by a binding spring 27, the jointed plug thus connected will ordinarily receive the minimum spaced prongs of any electrical device or appliance. Such, however, of greater spacing are as readily engageable with the plug. Grasping the plug at the rear portion and squeezing the same lightly, just sufficient to overcome the resistance of the tension exerted by the binding spring 27, will permit extension of the respective forward ends of the halves A and B to meet the required width of the spacing demanded by the prongs.

25 Figures 8 and 9 illustrate the attachment plug modified in some respects. In principle and operation, however, it embodies like features as the former. The principal difference between the two being that the latter has its separate half portions interconnected in manner varying with the former. In the latter, the spring tensioning of the respective halves is accomplished by means of a combined fulcrum and C-shaped spring 29 cooperatively positioned within the halves A and B as 35 at 28, and whereby the spring normally urges the forward ends of the halves A and B together, and, at the same time, securely engages said halves to one another.

Shoulders 30 of any desired shape and style may 40 also be provided as shown, on either type of attachment plug. They serve a useful purpose when the plug is connected to an appliance having a wire reeling device, in which case the shoulder prevents the plug from being drawn into the 45 reel when the wire is drawn therein.

Readily produced from materials obtainable in the open market and at no great expense, light in weight, compactly built and well constructed, the plug commends itself for its universal adaptation 50 and satisfaction in operating results.

I am aware that slight modifications may from time to time be made in the details of structure without departing, however, from the scope of the present invention, and as defined in the claims which are appended hereto. Hence, I do not limit my present invention to the exact description of construction herein disclosed, but what I do claim is:—

1. An attachment plug comprising a pair of relatively movable and detachably connected 10 tubular sections, spring means surrounding and removably mounted on said sections for holding them together, resisting relative movement thereof and permitting said sections to be separated when removed therefrom, separable fulcrum portions embodied in opposed portions of said sections for affording relative pivotal movement of the latter when said spring means is in place and a bodily separation of said sections upon removal of the said spring means, and contact members 20 enclosed in said sections, each of said sections having one opening affording engagement of the contact member thereof with a contact post of an electrical appliance, and another opening affording connection of said contact member with a 25 flexible electrical conductor.

2. An attachment plug comprising a pair of relatively movable and detachably connected tubular sections, spring means surrounding and removably mounted on said sections for holding them 30 together, resisting relative movement thereof and permitting said sections to be separated when removed therefrom, separable male and female fulcrum portions embodied in opposed portions and between the ends of said sections for afford- 35 ing relative pivotal movement of the latter when said spring means is in place and a bodily separation of said sections upon removal of the said spring means, and contact members enclosed in said sections, each of said sections having one 40 opening affording engagement of the contact member thereof with a contact post of an electrical appliance, and another opening affording connection of said contact member with a flexible electrical conductor, each of said sections being 45 longitudinally divided into halves each of which is provided with one of said fulcrum portions and means for securing said halves together.

JOHN P. OGLE. 50
